UNITED STATES PATENT OFFICE.

P. A. ROYCE, OF BUFFALO, NEW YORK.

IMPROVEMENT IN MECHANICAL MEDICATORS.

Specification forming part of Letters Patent No. 58,301, dated September 25, 1866.

To all whom it may concern:

Be it known that I, P. A. ROYCE, of the city of Buffalo, county of Erie, and State of New York, have invented a new and Improved Mechanical Medicator; and I do hereby declare that the following is a full and exact description thereof, reference being had to the accompanying drawings and to the letters of reference marked thereon.

The nature of my invention relates to an apparatus by which a variety of diseases in various forms may be successfully treated, whether acute or chronic, and without any inconvenience or unpleasant sensations to the patients, and which could not be reached by the old method, to all of which my improved apparatus is peculiar, in applying remedies both externally and internally. By my invention many diseases may be reached at any locality of the system—a decided advantage over the old method of applying remedies.

My invention has for its object the treatment of diseases by applying locally to both the external and internal parts and organs (so far as they are accessible to mechanical appliances) liquids, vapors, gases, or finely-commuted powders for anæsthetic and other medical purposes; the generating of gases and vapors from liquid and solid substances for said purposes in a convenient, safe, and economical manner, and the use of atmospheric pressure, or of the exhaustion or rarefaction thereof, applied to local affections and diseased organs in remedial treatment; and it consists in the combination of a double-acting piston-pump with suitable devices and appliances, hereinafter described, for generating medical vapors and applying the same, either by themselves or mixed with atmospheric air, forming a compact, portable, and convenient apparatus for the purpose.

Figure 1 is a side elevation of my instrument in connection with a portion of the apparatus used for the generating of gas. Fig. 2 is a plan or vertical view of the instrument alone. Fig. 3 is a transverse vertical section through the same. Fig. 4 is a detached view of a sliding cap, and Fig. 5 of a thimble or nozzle used over the perforated pipe G, Fig. 1, for purposes hereinafter to be described. Fig. 6 is a plan view, and Fig. 7 a sectional elevation, of a spirit-lamp of ordinary construction. Figs.

8 and 9 are a vertical section and a plan view of a cup to be used with my apparatus for dry-cupping or drawing blood. Figs. 10 and 11 are side views of jars used in connection with the generating-cups, Fig. 14, and the pumping apparatus, Fig. 1, for producing ozone. Fig. 12 is an inverted or bottom view, and Fig. 13 a sectional elevation, of a heater to be used in connection with the apparatus.

Like letters refer to corresponding parts in the different figures.

As represented in the drawings, A is a stand or base of any suitable or convenient form, which supports the upright cylinder B, which is closed at the top and provided with a diaphragm or partition, y, a little distance above the stand, which divides it into an upper closed cylinder and a lower or supplementary chamber, the bottom of which is a removable diaphragm or cup, T. The cylinder B is provided with a piston, S, and rod E, which is connected above with hand-lever D and fulcrum-standard C, Fig. 1, and also with two side chambers, F K, (best shown in Fig. 3,) which extend from the top to a point slightly below the diaphragm y, where F is provided with an induction-port, H, and K with an eduction-orifice, L, both of a conical form at their termination, to admit of convenient connection with elastic tubes or other extension.

Valves N P and O R, of any suitable construction, communicate between chamber F and cylinder B, opening into the latter, and from said cylinder into chamber K, so that when the piston is worked the apparatus performs the functions of a double-acting pump.

This pump may be used for compressing air to apply local pressure to any affected part by connecting an air-bag with the orifice L by means of a suitable tube; or, in like manner, any medicated vapor or anæsthetic agent may be applied by generating the same in the supplementary chamber T in the following manner: The lower portion of this chamber consists of a cup closely fitting the sides of the cylinder B, which forms a tight receptacle for any liquid or other material which it is desired to vaporize or otherwise employ.

Heat is applied to the bottom U by means of a spirit-lamp, when the volatilized portions which fill the chamber T are drawn into F through the small tube or orifice V,

Fig. 3, (the induction - orifice H being previously closed by suitable cap,) and thus, by the action of the pump, is conveyed through L to the point required. As a supply of air is usually required in mixture with the medicated vapors employed, and especially in applying anaesthetic vapors to modify and regulate their influence, I provide for the introduction of air in any quantity required, and for graduating the amount with great nicety by means of a tube, G, Figs. 1 and 3, having a row of perforations, *i'*, on its side or sides, and provided with a cap, W, Fig. 4, closed at one end. The open end being placed on that of the tube G closes it, and by sliding it farther on or off more or less of the perforations are covered, thus graduating the air-admitting space.

Thus the chamber T may be made the receptacle of any material of a medical nature, and by admitting a requisite quantity of air, as described, and by the application of heat, if required, vapors therein formed will be taken through the pump and conveyed to the lungs, or any other part, internally and externally; and the apparatus may also be used for fumigation by generating by heat the fumes or gases from the solid substances and discharging them through a flexible tube connected with the nozzle L.

It will be observed that this instrument acts equally well for exhausting or condensing air. Thus the cup *g*, Figs. 8 and 9, may be used upon the patient either for applying pressure of air to treat inflamed and congested parts by repelling the blood, or for exhausting the air, so as to cause the blood to flow to the part to which it is applied; and these different effects are produced by simply connecting the tube *h* with the orifice L for condensing, or with H for exhausting. By placing one of the limbs in an air-tight envelope and condensing the air within it, a uniform pressure is obtained, by which swellings or other enlargements may be reduced or medicated vapors and foments applied to the limb, while by the same apparatus, worked to rarefy the air, the contrary effect of attracting the blood to the part is produced, thus placing under the control of the medical practitioner, by a simple apparatus, very important remedial methods of treatment hitherto little used, and effected by the same action of the instrument simultaneously on different parts of the system, or on different patients.

The value of these functions of the apparatus is illustrated in the case of a swollen or inflamed breast, where pressure may be applied by condensing air in a suitable cup, or by an air-pad, while the apparatus is at the same time exhausting the air from the other breast, and bringing the blood into it, while repelling it from the affected one, thus restoring equilibrium to the circulation.

One very important use of this apparatus is to apply local pressure to the internal organs and pelvic viscera by connecting with the

nozzle L an elastic tube having at its opposite end an expansive india-rubber bladder. I first insert it into the natural passage till the affected part is reached, and then inflate it by the pump until sufficient pressure is attained. This forms a most effectual means of arresting uterine hemorrhage, as the inflation of the air-bladder may be made to completely close the vaginal passage and produce direct pressure on the uterine vessels. In this manner hemorrhoidal veins may be reduced without excision in any form, and at points above reach by ordinary means.

External pressure is attainable by the use of the air-bladder, bound upon the limb or body while collapsed, and afterward inflated. Anaesthetic vapors may be injected directly into the internal organs, or applied externally where local anaesthesia is required, and medicine in the form of powder or dust may thus be introduced into the throat, lungs, lower bowels, and pelvic viscera by simply connecting the eduction-tube of the apparatus with a bottle containing it.

One of the attachments of my apparatus is designed for generating ozone for direct inhalation from a tube connected with eduction-pipe of the apparatus, or for disseminating in the atmosphere of the room occupied by the patient.

Upon a suitable base, D, Fig. 14, two glass or earthen cups, F E, are fixed and nearly filled with water. Phosphorus is introduced into cup F, the pieces being exposed above the water in parts, when the glass jar N, Fig. 11, is inverted over it, with its neck inserted in the water of the cup. The jar M, Fig. 10, is in like manner inverted in the water in cup E, to form a purifier and receiver, as will be explained. The glass pipe L, Fig. 14, being connected with the nozzle L, Fig. 3, air is pumped through it into the jar F.

The chemical action which takes place between the phosphorus and the water produces ozone, which, by the introduction of air by the pump, is carried through pipe K into the jar E, where it is discharged in the water, the end of the pipe being submerged, and blown through it before it rises into the jar. The water purifies the ozone from any phosphorous acid remaining with it. The purified ozone passes out by the eduction-tube I to the patient, or into the air of the room, as desired. This forms a very simple and controllable means of generating this valuable medical agent, which has hitherto been almost unemployed, in consequence of the difficulty and danger attending its production and use in safe quantities.

What I claim as my invention, and desire to secure by Letters Patent, is—

1. The apparatus consisting of the pumping-cylinder B, chambers F K, provided with induction and eduction valves and orifices, with the supplementary or generating chamber T, connected with chamber F by the passage V, the whole combined, arranged, and

operating substantially in the manner and for the purpose herein set forth.

2. In combination with the above-described apparatus, the perforated air-pipe G and sliding cap W, operating in the manner and for the purpose specified.

3. In combination with the said apparatus,

the ozone-generator, Fig. 14, constructed and operating substantially as described.

P. A. ROYCE.
